(57) **CLAIM**

The ornamental design for a can opener, as shown and described.

DESCRIPTION

FIG. 1 is a front, left, and top perspective view of a can opener showing my design.

FIG. 2 is a back, left, and top perspective view thereof.

FIG. 3 is a front view thereof.

FIG. 4 is a back view thereof.

FIG. 5 is a left side view thereof.

FIG. 6 is a right side view thereof.

FIG. 7 is a top view thereof.

FIG. 8 is a bottom view thereof.

FIG. 9 is a perspective view thereof, showing a handle of the can opener rotated in a use status; and,

FIG. 10 is another perspective view thereof, showing two clamping arms of the can opener in an open position.

The broken lines in the drawings illustrate portions of the can opener that form no part of the claimed design.
